Primary Examiner — Deanna L Pratt(74) *Attorney, Agent, or Firm* — Banner & Witcoff, Ltd.(57) **CLAIM**

The ornamental design for a display screen with graphical user interface, as shown and described.

DESCRIPTION

The FIGURE is a front view of a display screen with graphical user interface showing the new design.

The broken line showing of the display screen illustrates the environment of the claimed design and forms no part thereof. The remaining broken lines illustrate portions of the graphical user interface that form no part of the claimed design.
